UNITED STATES PATENT OFFICE.

JOHN CHRISTOPHER TAPSCOTT, OF EL PASO, TEXAS.

TOUPEE AND WIG RETAINER.

1,378,147.

Specification of Letters Patent. Patented May 17, 1921.

Application filed August 25, 1920. Serial No. 405,896.

To all whom it may concern:

Be it known that I, JOHN CHRISTOPHER TAPSCOTT, a citizen of the United States, and a resident of El Paso, in the county of El Paso and State of Texas, have invented certain new and useful Improvements in Toupee and Wig Retainers, of which the following is a specification.

My present invention relates generally to 10 toupees or wigs, and more particularly to the manner in which the same is retained in place on the head, my primary object being the provision of an arrangement which will avoid the present use of a double faced 15 adhesive for this purpose.

The double faced adhesives commonly used at the present time require frequent change and have the effect of gumming and soiling the inner surface of the toupee or 0 wig next to the scalp, requiring the same to be frequently scrubbed and cleaned and often necessitating the use of solvents for cleaning purposes, both of which have the effect of decreasing the life of the wig.

25 It is the object of my present invention to avoid the necessity of a connection adhering to the inner surface of the toupee or wig and substitute therefor a mechanical holding means which will permit of the use 30 of a single faced adhesive whose adhering face is turned inwardly for engagement with the scalp.

In the accompanying drawing illustrating 35 my present invention and forming a part of this specification,

Figure 1 is a bottom plan view of a toupee or wig embodying my improvements and ready for use,

Fig. 2 is a fragmentary bottom plan view 40 of a portion thereof including one of the adhering connecting pieces,

Fig. 3 is an enlarged section taken on line 3—3 of Fig. 2, and

Fig. 4 is a plan view of a fragmentary 45 portion with the adhesive removed showing the mechanical connector secured to the wig.

Referring now to these figures my invention proposes an adhesive supporting mechanical connector consisting of a pair of 50 thin flat metal plates 10 and 11, hingedly connected along their inner adjacent sides as at 12 and provided with apertures adjacent to their outer sides and near their opposite ends as at 13 attached by threads 55 14 to the inner surface of a toupee or wig 15 at variously spaced points as shown in

Fig. 1. Thus by virtue of the points of connection with the toupee or wig and the fact that their inner edges are hingedly connected, the plates 10 and 11 can flex freely 60 with respect to one another for a purpose which will be now described.

The outer side edges of the plates 10 and 11 have spurs 16 located intermediate their ends and each outstanding in the same plane 65 with its respective plate, for extension through slits or openings 17 in an adhesive strip 18 which according to the present invention need have but a single adhesive face, with a smooth non-adhering surface toward 70 the inner surface of the wig.

In placing the several adhesive strips 18 in position they are first provided with the slits 17, and to extend the spurs 16 through these slits, the plates 10 and 11 are flexed 75 on their hinged edges so that after the spurs are passed through the slits of the adhesive strips, and after the plates are released they naturally assume a position more or less in alinement and thus prevent accidental withdrawal of the spurs.

In this way the adhesive strips 18 are effectively held in place with their adhesive surfaces turned innermost for engagement with the scalp when the toupee or wig is 85 placed in position and it becomes obvious that by virtue of the mechanical connection between the strips and the toupee or wig, I avoid the soiling and gumming of the wig now a common objection to the double 90 faced adhesive strips employed.

Furthermore my invention has another and distinct advantage in that it enables a toupee or wig to be held in place by spaced adhesive strips 18 held in connection with 95 the wig as I propose, and in materially less number than are required with the double faced adhesive strips employed at the present time.

I claim:

1. The combination with a toupee or wig, of attaching means including a pair of attaching plates hingedly connected along their inner edges and flexibly attached to the toupee or wig at the opposite ends of 105 their outer edges, spurs projecting from the outer edges of the plates intermediate their ends and each projecting in the plane of its respective plate, and an attaching strip slotted at spaced points to receive the spurs 110 therethrough, having a smooth face turned toward the adjacent surface of the toupee

or wig and an adhesive surface presented outwardly away from the toupee or wig as described.

5. The combination with a toupee or wig, of attaching means including a pair of plates movably hinged at their inner sides and flexibly attached at the opposite ends of their outer sides to the toupee or wig, spurs projecting from the outer edges of the 10 plate intermediate their ends, and attaching strips having spaced slits to receive the spurs and having adhesive surfaces presented away from the toupee or wig as described.
15. 3. Toupee or wig holding means including flexible members movably attached to and forming a permanent part of a toupee

or wig and provided with outstanding spurs, and scalp engaging connecting strips through portions of which the spurs are projected, having adhesive surfaces turned away from the toupee or wig as described. 20

4. Toupee or wig holding means including a pair of connecting plates movably attached to, and forming a permanent part of a toupee or wig, and flexibly connected at their adjacent edges to one another, said plates having outstanding spurs at their outer edges, and a renewable scalp engaging strip through which the spurs are extended, 25 having a single adhesive surface turned away from the toupee or wig. 30

JOHN CHRISTOPHER TAPSCOTT.
